UNITED STATES PATENT OFFICE.

JOHNSON ROSS CORBIN, OF PHILADELPHIA, PENNSYLVANIA.

PRINTING-MACHINE.

SPECIFICATION forming part of Letters Patent No. 640,634, dated January 2, 1900.

Application filed November 28, 1899. Serial No. 738,517. (No model.)

To all whom it may concern:

Be it known that I, JOHNSON ROSS CORBIN, a citizen of the United States, residing at Philadelphia, in the county of Philadelphia, State 5 of Pennsylvania, have invented new and useful Improvements in Printing-Machines, of which the following is a specification.

My invention relates to printing-machines, more particularly of the rotary type, and has 10 for its objects to provide certain novel embodiments in the construction and operation of the same, more particularly relating to multicolor-printing in connection with the production of newspapers and magazines, as 15 will be hereinafter more definitely set forth, and embraced in the claims appended hereto.

In an application for Letters Patent filed by me March 7, 1899, Serial No. 708,129, I have disclosed a novel apparatus for assembling a plurality of colors in predetermined spots upon yielding planographic transfer-surfaces preparatory to taking multicolor impressions therefrom at a single imprint; and my present invention is specifically designed 25 to utilize said broad idea in the production of multicolor newspaper-sheets or magazine-pages in which one side of the sheet or page will first receive the usual impression of reading matter in one-colored ink from a suitable 30 stereotype or electrotype form to be followed by a multicolor imprint upon the reverse side of said sheet or page and in substantially accurate register with the first imprint, said multicolor imprint being imparted at a single 35 impression and in as many as twelve distinct colors, if so desired, the said multicolor design being subsequently completed by imparting thereto the final print from what is termed the "key-plate." To accomplish this 40 result and obtain an imprint of as many as twelve colors is specifically the object of my present invention, and this I accomplish by employing two large cylinders rotating in unison, each carrying a plurality of yielding 45 planographic transfer-surfaces, upon which are assembled inks in six distinct colors in predetermined spots, an intermediate transfer-cylinder being provided for each large cylinder upon which said transfer-surfaces successively transfer their inks, said intermediate transfer-cylinders then transferring the 50 inks to a single-design surface on the print-

ing-cylinder, from which the imprint is made to the paper, each single combined transfer from the two intermediate transfer-cylinders 55 constituting a complete inking for a single impression.

In the drawing accompanying this specification the figure is a side elevation of a rotary printing-machine embodying my improved construction.

In the said drawing the reference-numeral 1 denotes the frame of the machine, in which are mounted two cylinders 2, identical in size and construction, each of which is adapted to 65 carry on its periphery a plurality of adjustable yielding planographic surfaces 3, preferably six in number, for each cylinder, the same constituting ink-transferring surfaces. Power is applied to the shaft of one of said 70 cylinders to rotate the same, intermediate gear-wheel 4 imparting a simultaneous rotation to the other cylinder.

A series of cylinders 5, carrying what I term "pattern-design forms," is provided for 75 each cylinder 2, preferably six in number, each pattern-design form receiving its ink from an independent inking-train 6, as shown.

Mounted in proximity to each other are two cylinders 7, each carrying a yielding planographic transfer-surface that contacts with the surfaces 3 on one of the cylinders 2, said cylinders 7 contacting with a common printing-cylinder 8, carrying a suitable form. Above said cylinder 8 is the usual impression-cylinder 9, while above the latter is a similar impression-cylinder 10, geared thereto by intermediate gear 11, as shown, a suitable printing-cylinder 12 completing the printing-couple for cylinder 10 and receiving its ink-supply from inking-train 13.

Above one of the cylinders 2 is located a printing-couple consisting of impression-cylinder 14 and printing-cylinder 15, the latter receiving its supply of ink from inking-train 95 16 in the usual manner, said printing-couple being geared to rotate in unison with the rest of the machine by means of gear 17 in mesh with one of the pattern form-cylinders 5, as shown.

When employed in printing from a web, as when printing both sides of a newspaper-sheet or a magazine-page, the web 18 is first led between printing-couple 14 15, where it receives

an ink impression on one side of the sheet, the form on cylinder 15 imparting, for instance, reading matter only. The web then passes between printing-couple 8 9, where it receives 5 an impression from cylinder 8 on the reverse side of the sheet, this impression being made up in the following manner: The design to be printed on this side of the web is produced in relief on the plate carried by cylinder 8, while 10 the surfaces of the pattern-design forms on cylinders 5 have been previously prepared in a predetermined pattern design, so that each pattern-design form will receive its particular colored ink from its inking-train 6 and de- 15 posit the same on each yielding surface 3 as it passes in contact therewith, the pattern-design forms being so arranged that each surface 3 will receive the different inks accurately in predetermined patches and will in 20 succession deposit said inkings on the transfer-surface of its cylinder 7, the said transfer-surfaces then depositing the inkings onto the plate or form on cylinder 8, each single combined transfer of cylinders 7 constituting a 25 complete inking for a single impression from said plate or form. It will thus be seen that with six cylinders 5 and six transfer-surfaces 3 for each cylinder 2 twelve different colors may be imparted to the plate or form on print- 30 ing-cylinder 8, said twelve colors being simultaneously printed upon the web in its passage between the printing-couple 8 9. The web then passes between printing-couple 10 12, the printing-cylinder 12 carrying what is termed 35 in color-printing the "key-plate" for the final printing in one color, preferably black, though said plate may also have thereon any reading or other matter that it is desired to print on this side of the web. It will thus be seen that 40 the web first receives the usual impression in one color on one side from printing-couple 14 15, then receives a complete multicolor print at a single impression from one plate on the reverse side of the web from that imparted by 45 printing-couple 8 9, and finally receives the key-plate impression to complete said multicolor print, as well as any desired reading or other matter, from printing-couple 10 12. It will be understood, however, that the form 50 or plate carried by printing-cylinder 8 may be so prepared that the resultant multicolor impression from it will be a complete and finished product in itself, the use of the printing-couple 10 12 not being necessary in all cases 55 for the production of a complete multicolor print, as it is frequently desirable for special purposes to produce a complete multicolor print from one plate with a single impression.

By employing a plurality of, say, six transfer-surfaces on each of cylinders 2 it will be seen that six separate and complete inkings will be imparted to the printing-cylinder 8 for each rotation of cylinders 2, while the use of a different-colored ink in each inking-train 6 will impart to said cylinder 8 twelve distinct colors for each impression. It is sometimes desired, however, to ink certain colors more

heavily than others, which may be accomplished by employing the same color in two or more of the trains 6, the pattern-design forms 70 therefor being arranged to deposit in the same spot or spots on surfaces 3, thus providing a double inking for said color for each impression. Thus, for instance, two colors may be inked twice and eight colors once or three 75 colors twice and six colors once. In fact, this feature may be varied at will to suit the requirements of the multicolor subject, the portions where a small quantity of ink will suffice receiving but a single inking, while those portions requiring a greater quantity of ink 80 may receive additional inkings by duplicating the pattern-design forms and colors.

While I have shown and described my machine as adapted more particularly for web-printing, it will be understood that the same 85 may be used for printing upon separate sheets, though in this event a suitable feed-board, grippers, tapes, &c., will be required, as is well understood in the printing art. 90

Having thus described my invention, what I claim as new, and desire to secure by Letters Patent, is—

1. In a printing-machine, means for imparting a multicolor print at a single impression, a plurality of carriers each carrying a plurality of surfaces each inked in multicolor, and means for transferring said inkings successively to the printing means, each single combined transfer from said surfaces constituting a complete inking for a single impression. 95

2. In a printing-machine, means for imparting a complete multicolor print at a single impression, a plurality of carriers each carrying a plurality of surfaces each inked in multicolor, and means for transferring said inkings successively to the printing means, each single combined transfer from said surfaces constituting a complete inking for a single impression. 105

3. In a printing-machine, a single printing-cylinder carrying a suitable form or plate for imparting a multicolor print at a single impression, a plurality of cylinders each carrying a plurality of surfaces each inked in multicolor, and means for transferring said inkings successively to the printing-cylinder, each single combined transfer from said surfaces constituting a complete inking for a single impression. 115

4. In a printing-machine, a single printing-cylinder carrying a suitable form or plate for imparting a complete multicolor print at a single impression, a plurality of cylinders each carrying a plurality of surfaces each inked in multicolor, and means for transferring said inkings successively to the printing-cylinder, each single combined transfer from said surfaces constituting a complete inking for a single impression. 125

5. In a printing-machine, means for imparting a multicolor print at a single impression, a plurality of carriers each carrying a plurality of surfaces each inked in multicolor, and

intermediate transfer-surfaces receiving the supplies of inks and transmitting them successively to the printing means, each single combined transfer from said intermediate surfaces constituting a complete inking for a single impression.

6. In a printing-machine, means for imparting a multicolor print at a single impression, a plurality of cylinders for assembling a plurality of supplies of ink in multicolor, and intermediate transfer-surfaces receiving the supplies of ink and transmitting them successively to the printing means, each single combined transfer of said intermediate surfaces constituting a complete inking for a single impression.

7. In a printing-machine, a single printing-surface for imparting a multicolor print at a single impression, a plurality of cylinders for assembling a plurality of supplies of ink in multicolor, and intermediate transfer-cylinders receiving the supplies of inks and transmitting them successively to the printing-surface, each single combined transfer of said intermediate cylinders constituting a complete inking for a single impression.

8. In a printing-machine, a single printing-cylinder carrying a suitable form or plate for imparting a multicolor print at a single impression, two transfer-cylinders for assembling a plurality of supplies of ink in multicolor, and intermediate transfer-cylinders receiving the supplies of inks and transmitting them successively to the printing-cylinder, each single combined transfer of said intermediate cylinders constituting a complete inking for a single impression.

9. In a printing-machine, a single printing-surface for imparting a multicolor print at a single impression, a plurality of cylinders each carrying a plurality of transfer-surfaces, a plurality of pattern-design forms for each transfer-cylinder successively contacting with the transfer-surfaces thereon, a separate inking-train for each pattern-design form, and intermediate transfer-cylinders receiving the supplies of inks from the transfer-surfaces and transmitting them successively to the printing-surface, each single combined transfer of the intermediate cylinders constituting a complete inking for a single impression.

10. In a printing-machine, a single printing-surface for imparting a multicolor print at a single impression, a plurality of cylinders each carrying a plurality of yielding planographic transfer-surfaces, cylinders carrying a plurality of pattern-design forms successively contacting with said transfer-surfaces, and intermediate transfer-cylinders receiving the supplies of inks from said transfer-surfaces and transmitting them successively to the printing-surface, each single combined transfer of the intermediate cylinders constituting a complete inking for a single impression.

11. In a printing-machine, the combination of a single printing-surface for imparting to

a web or sheet a multicolor print at a single impression, a plurality of transfer-surfaces for assembling each a plurality of supplies of ink in multicolor, intermediate transfer-surfaces receiving the supplies of inks and transmitting them successively to the printing-surface, each single combined transfer of said intermediate surfaces constituting a complete inking for a single impression, a printing-couple for imparting to said web or sheet an impression on the opposite side, and a printing-couple for imprinting the design to complete the multicolor print in register after the imprint of said multicolor print.

12. In a printing-machine, the combination of a single printing-surface for imparting to a web or sheet a complete multicolor print at a single impression, a plurality of transfer-surfaces for assembling a plurality of supplies of ink in multicolor, intermediate transfer-surfaces receiving the supplies of inks and transmitting them successively to the printing-surface, each single combined transfer of said intermediate surfaces constituting a complete inking for a single impression, and a printing-couple for imparting to said web or sheet an impression on the opposite side.

13. In a printing-machine, the combination of a single printing-cylinder carrying a suitable form or plate for imparting to a web or sheet a multicolor print at a single impression, two transfer-cylinders for assembling a plurality of supplies of ink in multicolor, intermediate transfer-cylinders receiving the supplies of inks and transmitting them successively to the form or plate on the printing-cylinder, each single combined transfer of said intermediate cylinders constituting a complete inking for a single impression, a printing-couple for imparting to said web or sheet an impression on the opposite side, and a printing-couple for imprinting the design to complete the multicolor print in register after the imprint of said multicolor print.

14. In a printing-machine, the combination of a single printing-cylinder carrying a suitable form or plate for imparting to a web or sheet a complete multicolor print at a single impression, two transfer-cylinders for assembling a plurality of supplies of ink in multicolor, intermediate transfer-cylinders receiving the supplies of inks and transmitting them successively to the form or plate on the printing-cylinder, each single combined transfer of said intermediate cylinders constituting a complete inking for a single impression, and a printing-couple for imparting to said web or sheet an impression on the opposite side.

In testimony whereof I have hereunto set my hand in the presence of two subscribing witnesses.

JOHNSON ROSS CORBIN.
